UNITED STATES PATENT OFFICE.

HARRY T. KRAKAU, OF CLEVELAND, OHIO, ASSIGNOR TO THE NATIONAL MALLEABLE CASTINGS COMPANY, OF CLEVELAND, OHIO, A CORPORATION OF OHIO.

ENGINE-TENDER PLATFORM.

1,144,713.

Specification of Letters Patent. Patented June 29, 1915.

Application filed March 9, 1912. Serial No. 682,620.

To all whom it may concern:

Be it known that I, HARRY T. KRAKAU, a citizen of the United States, residing at Cleveland, Cuyahoga county, Ohio, have invented a new and Improved Engine-Tender Platform, of which the following is a specification, reference being had to the accompanying drawings, in which—

Figure 1 is a plan view of my improved platform, and Fig. 2 is an enlarged section on lines II—II of Fig. 1.

My invention relates to platforms or aprons between engines and tenders and is designed to provide a platform which will 15 adjust itself to changes of level and direction between the engine cab deck and the tender deck by a telescopic and laterally 20 slideable joint.

In the present form of aprons or platforms in use between the engine and tender 25 the constant change of level between the cab deck and the tender deck frequently causes the apron to be cocked at a sharp angle from the engine deck or to leave a gap 30 between the tender deck and the apron, both of these conditions being a constant source of danger to the fireman, as he may thereby trip over the apron or catch his foot in the gap and be thrown from the train or 35 otherwise injured. These disadvantages are obviated by my improved construction.

Referring to the drawings, 2 indicates the engine, 3 the tender and 4 the coupling means.

5 is the cab deck and 6 is the tender deck. At the rear of the engine deck are the pivot lugs 7 from which depends the apron 8. This apron 8 has a recess 9 at its outer edge adapted for the admission of the 40 apron or web 10 which is pivotally attached by the lugs 11 to the tender 3.

When the engine and the tender are coupled, the apron 8 is held in a horizontal position, and the web 10 is caused to enter the 45 recess 9 of the apron 8. The plates comprising the apron 8 and web 10 are rigid, so that the apron 8 and the web 10 will mutually

sustain each other when the web 10 has entered the recess 9, and at the same time, there is provided a telescoping and laterally slideable joint between the parts. Hence, it will be seen that the platform comprised of these two parts 8 and 10 will always adjust itself to the unequal levels of the cab and tender decks, and that this adjustment will not only be vertical and horizontal, but will also be lateral, so that not only inequalities of level, but also changes of direction, such as occur during rounding of curves, will be provided for.

What I claim is:

1. An engine tender platform comprised of two webs, the said webs having a slot and recess engagement and admitting of vertical and lateral movement of the engine 65 and tender without drawing apart.

2. An engine-tender platform comprised of two webs, one end of each of said webs being pivotally attached to the engine and tender respectively, one of said webs being adapted to take about the other at its free end, and the free ends of said webs being mutually self-supporting.

3. An engine-tender platform comprised of a recessed member pivoted to the engine, 75 and a web pivoted to the tender, said web having its free end entered in the recessed member.

4. An engine-tender platform comprised of pivoted plates attached to the engine and 80 tender respectively, and telescopic means for supporting said plates and for providing for relative lateral, vertical, and horizontal movement of the engine and tender.

5. An engine tender platform consisting 85 of pivoted members attached to the engine and tender respectively, one of said members being adapted to take about the other, the said members comprising a telescoping and laterally slideable joint.

HARRY T. KRAKAU.
